UNITED STATES PATENT OFFICE.

WILLIAM T. EDWARDS, OF SAN DIEGO, CALIFORNIA.

HAIR-PIN.

Specification of Letters Patent. Patented Feb. 20, 1917.

1,216,970.

Application filed October 23, 1916. Serial No. 127,266.

To all whom it may concern:

Be it known that I, WILLIAM T. EDWARDS, a citizen of the United States of America, residing at San Diego, in the county of San Diego and State of California, have invented certain new and useful Improvements in Hair-Pins, of which the following is a specification.

This invention relates to hair pins and its object is to provide an improved article of this nature constructed in such manner that it will not only more effectively hold the hair in proper position but will be effectively held against accidental dislodgment from the hair.

Further objects and advantages of the invention will be set forth in the detailed description which now follows:

The figure shown in the accompanying drawing is a front face view of my improved hair pin.

Referring to the drawing, it will be seen that the hair pin is made of a single piece of wire and that the bight portion of this wire is bent upon itself to form a central prong 5 above which the wire is outwardly flared and lies at an acute angle to the median line of the hair pin forming the portions 6. The portions 6 are continued to form inwardly directed shoulders 7 and above these shoulders the two parts of the wire are twisted into engagement with each other at 8 to form a stiffening and reinforcing member which prevents separation of the outer sides of the hair pin. Above the twisted portion 8 the wire is bent outwardly and downwardly in opposite directions at 9 and 10 and is then bent outwardly at 11 and inwardly at 12 to form portions conforming in their general outline to the outer sides of the flaring portions 6 and shoulders 7 and is then extended downwardly for a considerable distance to form the side prongs 13 and 14.

From the foregoing description it will be seen that I have provided a three prong hair pin with the resultant advantage that more strands of hair may be engaged thereby than with the two prong hair pin so that the hair is more effectually held in the desired position. In addition, the central prong 5 depending between the prongs 13 and 14 forms two entrance channels 15 and 16 through which the hair passes. The flaring portions 6 acting in conjunction with the portion 12 constitute restricted passages

17 and 18 into which the hair is more or less compressed as the pin is pushed into place so that when the hair finally reaches the upper portions of the passages 17 and 18, 60 the tendency to expand causes it to move behind the shoulders 7 and since these shoulders 7 lie at an obtuse angle to the median line of the hair pin, it follows that the hair pin will not become readily disengaged from 65 the hair but that, upon the contrary, more force is required to remove the hair pin than is required to place the hair pin in position and considerably more pull is necessary to remove the hair pin than is necessary to remove a hair pin of the ordinary type. 70

While the elements shown and described are well adapted to serve the purposes for which they are intended, it is to be understood that the invention is not limited to 75 the precise construction set forth but includes within its purview whatever changes as fairly come within the spirit of the appended claims.

Having described my invention what I 80 claim is:—

1. A hair pin made from a single piece of wire, the opposite ends of which constitute prongs and the bight portion of which is bent to form a central prong then bent to 85 form outwardly divergent portions which lie at an acute angle to the median line of the hair pin, then bent inwardly to form shoulders that lie at an obtuse angle to the median line of the hair pin and are then continued to the first named prongs, that portion of the hair pin at the juncture of the divergent portions and the shoulders lying in spaced relation to the first named prongs and all of the portions of the hair pin lying 90 in substantially the same transverse plane. 95

2. A hair pin made from a single piece of wire, the opposite ends of which constitute prongs and the bight portion of which is bent to form a central prong then bent to 100 form outwardly divergent portions which lie at an acute angle to the median line of the hair pin, then bent inwardly to form shoulders that lie at an obtuse angle to the median line of the hair pin and are then continued to the first named prongs, said first named prongs comprising outwardly bent portions which conform to the outline of the divergent portions and the shoulders and lie in spaced relation thereto, all of the portions 105 of the hair pin lying in substantially the same transverse plane. 110

3. A hair pin made from a single piece of wire and bent at its bright portion to form a central prong, then bent to form outwardly divergent portions which lie at an acute angle to the median line of the hair pin, then bent inwardly to form shoulders that lie at an obtuse angle to the median line of the hair pin, then bent to twisted formation and then bent outwardly and downwardly to form side prongs, all of the portions of the hair pin lying in substantially the same transverse plane.
4. A hair pin made of a single piece of wire and bent at its bright portion to form a central prong, then bent to form outwardly divergent portions which lie at an acute angle to the median line of the hair pin, then bent inwardly to form shoulders that lie at an obtuse angle to the median line of the hair pin, then bent to twisted formation and then bent outwardly and downwardly to form side prongs, said side prongs

comprising bent portions which conform to the outline of the divergent portions and the shoulders, all of the portions of the hair pin lying in substantially the same transverse plane. 25

5. A hair pin made of a single piece of wire and bent to form side prongs and a central prong, said side prongs and said central prong being bent to such shape as to constitute receiving passages, constricted passages above said receiving passages and abrupt shoulders at the upper ends of the constricted passages, all of the portions of the hair pin lying in substantially the same transverse plane. 30 35

In testimony whereof I affix my signature in presence of two witnesses.

WILLIAM T. EDWARDS.
